UNITED STATES PATENT OFFICE.

FRANK L. FURBUSH, OF WESTFORD, MASSACHUSETTS, ASSIGNOR TO C. G. SARGENT'S SONS CORPORATION, A CORPORATION OF MASSACHUSETTS.

DEVICE FOR STRIPPING STOCK FROM CONVEYER APRONS.

Application filed September 14, 1922. Serial No. 588,295.

To all whom it may concern:

Be it known that I, FRANK L. FURBUSH, a citizen of the United States, residing at Westford, in the county of Middlesex and 5 State of Massachusetts, have invented a new and useful Device for Stripping Stock from Conveyer Aprons, of which the following is a specification.

This invention relates to a constantly operating device for stripping the stock from 10 a wire or perforated conveyer used in a drier or the like.

The principal object of the invention is to provide an arrangement which will always 15 remain in contact with the conveyer for stripping off the stock. This has presented some difficulty in connection with the class of conveyers which run over polygonal drums because the ordinary strippers are 20 sometimes out of contact with the apron that runs over such a drum. If the stock is not entirely stripped off it is carried back into the machine on the lower strand of the conveyer and the fans blow it around and 25 get some of it into the steam coils. This not only ruins the stock but it also clogs up the steam coils and reduces their efficiency. Beaters have been used heretofore on a round drum at the end of the conveyer for 30 this purpose and naturally work well because there is no tendency to lift the beater away from the drum.

One of the important objects of this invention is to modify the beater so that it 35 can be employed with a polygonal drum. Another object is to so arrange a doffer apron that it can be attached to this type of machine instead of the beater.

Further objects and advantages of the 40 invention will appear hereinafter.

Reference is to be had to the accompanying drawings, in which—

Fig. 1 is an end view of a drier apron showing a beater or stripper of my improved 45 construction used in connection therewith for stripping the stock from the wire;

Fig. 2 is a side view of the same; and

Figs. 3 and 4 are similar views of a doffer apron used in the same way.

50 Referring first to Figs. 1 and 2, I have shown the invention as applied to a drier 10 having a wire or perforated conveyer 11 carried on two sprocket chains 12 which run over drums 13 shown as hexagonal.

One is located at each end although only 55 one end is shown.

For removing the stock I have shown a rotary beater 14 having a plurality of beating arms extending therefrom and mounted on a shaft 15. At each end of the beater 60 14 runs a pulley 16 loose on the beater shaft 15. This pulley is designed to contact with the sprocket chain 12 in all positions of the drum 13 and therefore controls the position of the beater and keeps it in contact with 65 the conveyer at the discharge end thereof as shown.

In order to permit of this action a shaft 17 is provided with two pulleys connected together and running loose on the shaft. 70 The outer pulley 18 receives power through a belt 19 from a jack shaft or motor, not shown. The inside pulley 20 which is fixed to it to rotate with it is provided with a belt 21 operating a pulley 22 fixed on the shaft 75 15 to transmit power to the beater.

The beater shaft 15 is mounted in bearings 25 on arms 26 which are pivoted on the shaft 17 and free to swing thereon. It will be seen therefore that the pulleys 16 running 80 on the sprocket chains move out and in, in accordance with the rotation of the drum 13. At all times the beater arms, the ends of which run in the same circle as the pulleys 16, are in position to engage the conveyer 85 and effectively remove the stock therefrom. The motion of the beater back and forth caused by the angularity of the drum can take place as stated without changing the tension on the belt 21 and thus without 90 interfering with the operation of the beater or stripper.

In the form shown in Figs. 3 and 4, the invention is shown as applied to the same kind of a conveyer which I have numbered 95 in the same way and the power is transmitted also to the doffer apron 40 in the same way through a belt 41. This doffer apron 40 runs on two pairs of cylinders 42 parallel with each other on transverse shafts 100 43 at the two ends of the doffer apron. These shafts are supported between apron sides 44 fixed to the frame of the drier but are movable with respect thereto. One of them is carried by two links 45 and the other 105 by two links 46 freely depending from the frame 47 attached to the delivery end of the drier outside. A pulley is located on one

of the shafts 43 and thus the belt 41 drives the doffer apron continuously. In this case also there is an apron pulley 49 riding against the sprocket on the drum or the surface of the drum itself as in the other case to keep the intake side of the apron constantly in contact with the conveyer as in Figs. 1 and 2. The operation is the same and the results are the same except for the fact that this apron works like any other doffer apron and conveys the stock away instead of beating it down from the conveyer.

From this it will be understood that I have provided means whereby the removing device for the stock can be kept in operative position at all times even though the conveyer runs over a polygonal drum or even if it were located on an irregularly acting device or an eccentric one. This permits of entirely stripping the stock from the conveyer and keeping it from going back into the machine.

Although I have illustrated and described only two forms of the invention, I am aware of the fact that other modifications can be made therein by any person skilled in the art without departing from the scope of the invention as expressed in the claims. Therefore, I do not wish to be limited to all the details of construction herein shown and described, but what I do claim is:—

1. The combination with a conveyer and a non-circular rotary device over which the conveyer passes at one end, of movable means adjacent to said rotary device for stripping the stock from the conveyer, said movable means being hung from above to rest against the conveyer as it passes over said rotary device and having a wheel for regulating its distance from the conveyer arranged to move with the conveyer back and forth as it passes over at the end.

2. The combination with a drier conveyer and a non-cylindrical drum over which it passes at one end, of a stripping device

for removing the stock from the conveyer comprising a shaft, a rotary element on said shaft resting against the conveyer, and means for supporting said shaft freely in such position that it will act by gravity to swing back against the conveyer when moved outwardly therefrom by the motion of the conveyer itself.

3. The combination with an endless conveyer and a polygonal drum over which said conveyer moves, of a doffer apron for removing the stock from the conveyer, a shaft over which said apron passes and by which it is moved and controlled, a pulley on said shaft, a belt and pulley for operating the pulley and shaft, and means freely hung to swing from above for supporting said apron in a position to bear against the conveyer on the drum by the action of gravity at all times.

4. The combination with a conveyer for fibrous material and a drum over which it passes at one end, of an endless doffer apron comprising a shaft, a pair of wheels on said shaft resting against the conveyer, and means for supporting said shaft freely in such position that the doffer apron thereon will be caused by gravity to swing back against the conveyer when moved outwardly therefrom by the motion of the conveyer itself.

5. The combination with an endless conveyer and a polygonal rotary device over which the conveyer passes at one end, of movable means adjacent to said rotary device for stripping the stock from the conveyer, said movable means being hung freely above and from a point back of the end of the conveyer to rest against the conveyer as it passes over said rotary device and having a wheel for regulating its distance from the conveyer.

In testimony whereof I have hereunto affixed my signature.

FRANK L. FURBUSH.
